UNITED STATES PATENT OFFICE.

EDWYN ANTHONY, OF JERSEY CITY, NEW JERSEY, ASSIGNOR TO R. HOE & CO., OF NEW YORK, N. Y.

PRINTING-MACHINE.

SPECIFICATION forming part of Letters Patent No. 324,975, dated August 25, 1885.

Application filed May 18, 1883. (No model.)

To all whom it may concern:

Be it known that I, EDWYN ANTHONY, a subject of the Queen of Great Britain, residing at Jersey City, county of Hudson, State of New Jersey, have invented a new and useful Improvement in Printing-Machines, of which the following is a specification.

My invention consists in an improvement or modification of that contained in Patent No. 222,880, dated March 4, 1879. In the said patent a web is printed on one side, and then by means of inclined turners it is returned to the same printing-surface, or to one parallel therewith, and receives an impression on the other side. The present invention applies only when the web is broad enough to have two or more pages abreast printed thereon.

The invention consists in the combination, with printing mechanism, of means for longitudinally splitting a web into two or more webs before the second impression is imparted thereto, and for reversing each strip or narrow web separately, and in the combination, with a single turning-bar, of a plurality of turning-bars arranged at appropriate angles thereto, which preferably will be right angles, and guiding-rollers, all of which is hereinafter fully explained.

By my invention it is possible to have the 30 pages imprinted on the web in orders which are impossible when it is reversed, as described in the said patent. For instance, most of the arrangements exhibited in table W of an application for Letters Patent for an improvement in printing-presses (filed by me on or about April 30, 1883) are impossible when the web is reversed, as shown in the said patent.

Figured represents a side elevation, and Fig. 2 a bottom plan view, of a machine illustrative 40 of my invention, Figs. 3 and 4 showing plan views of modifications of the reversing apparatus shown in Figs. 1 and 2.

Referring to Figs. 1 and 2, P indicates the form-cylinder; D M, the impression-cylinders; 45 C C, the slitting mechanism for longitudinally splitting or dividing the web. It consists of two cylinders, the lower having grooves and the upper co-operating circular knives which split the web into three (in this instance) equal 50 strips or webs.

E L denote rollers for conducting the web

respectively to and from the reversing apparatus.

F indicates a fixed cylinder or turning-bar inclined to the axis of the form-cylinder, and 55 having a common tangent plane with the roller L.

K' K² K³ indicate three shorter fixed cylinders or turning-bars arranged parallel to one another. Their axes are also inclined to that 60 of the form-cylinder, and they are fixed at right angles to the turning-bar or cylinder F, as shown in the drawings. All three turning-bars or cylinders must have a common tangent plane with the roller L, and the roller G must 65 be fixed so as to have one common tangent plane with the turning-bar or cylinder F, and another with the turning-bars or cylinders K' K² K³, all of which things are manifest from an inspection of the drawings. 70

A marks the web. After longitudinal splitting, one side of each of the then three webs is denoted by A' A² A³, respectively, and the other side by B' B² B³, respectively.

The course of the web is easily traced. It 75 first passes between the longitudinal slitting mechanism C C, and then round the impression-cylinder D, thereby getting printed on one side. It next passes round roller E to the turning-bar or cylinder F, thence round the 80 roller G, and from there the three parts of the paths of the web diverge. The strip A' passes round the turning-cylinder K' and thence round the roller L, the strip A² round the turning-bar K² and thence round the roller L, and the strip 85 A³ round the turning-bar K³ and thence round the roller L. Thus all three strips pass round L, and thence they go round the impression-cylinder M, thereby receiving an impression on their other sides. 90

It is evident that the slitting mechanism C 95 may be placed at any convenient part of the path of the webs prior to its reaching the point where the severed strips diverge. Thus the roller G might have suitable longitudinal slitters working in connection with it.

In Figs. 1 and 2 the three webs or strips A' A² A³ travel different distances in passing through the reverser. By using three rollers, G' G² G³, as shown in Fig. 4, in place of the 100 single roller G, each strip will travel the same distance, and this distance will be much less

than if the web had been reversed in one piece, as in the aforesaid patent. By using three shorter parallel turning-bars or cylinders in place of the one long turning-bar or cylinder 5 F—in other words, by using three entirely independent turners—the distance of travel may be still further reduced; but the length of travel in Fig. 4 is not in most cases inconveniently great, and when the order of the pages 10 only needs to be considered, then the apparatus in Figs. 1 and 2 is most appropriate.

Fig. 3 illustrates the case of a three-breadth web which has been divided or slit longitudinally into two portions only. Similarly to the 15 preceding case, the roller G may be replaced by two rollers and the single turning-bar or cylinder F by two turning-bars or cylinders.

In the figures the various webs are always 20 reversed without receiving any lateral transfer; but it is obvious that by suitably moving the turning-bars or cylinders K' K² K³ parallel to themselves (and corresponding rollers) the positions of the webs may be interchanged, &c. Thus the web A' might be caused to pass over 25 the roller L opposite to the position of A² before it enters the apparatus, and similarly the web A³ may pass over roller L opposite to the position of A' before entering the apparatus; or all the webs may undergo any desired lat-

eral transfer, &c., and of course the webs may 30 be transversely severed before they pass through the reverser, being (after cutting) suitably conducted by tapes; and it is clear that the webs after reversal may receive their second impression from another cylinder parallel 35 to the form-cylinder P, instead of, as in the figure, from the form-cylinder P itself.

What I herein claim as my invention is—

1. In a web-printing machine, the combination, with printing mechanism, of mechanism 40 for longitudinally slitting or dividing a web into narrow webs before it has received its second impression, and mechanism for reversing the separate webs so that their paths of travel are not the same while being reversed, all substantially as described.

2. The combination, with a single turning-bar or cylinder, of a plurality of turning-bars or cylinders at appropriate angles thereto and parallel to one another, and rollers to guide 50 the webs between said bars or cylinders, whereby a plurality of webs running side by side are reversed, all substantially as described.

EDWYN ANTHONY.

Correction in Letters Patent No. 324,975.

It is hereby certified that Letters Patent No. 324,975, granted August 25, 1885, upon the application of Edwyn Anthony, of Jersey City, New Jersey, for an improvement in "Printing Machines," was erroneously issued to "R. Hoe & Co., its successors or assigns;" that said Letters Patent should have been issued to *R. Hoe & Co., their heirs or assigns*; that this correction has been made in the records of the case in the Patent Office, and that the said Letters Patent should be read to conform thereto.

Signed, countersigned, and sealed this 1st day of September, A. D. 1885.

[SEAL.]

G. A. JENKS,
Acting Secretary of the Interior.

Countersigned:

M. V. MONTGOMERY,
Commissioner of Patents.
